Raymond F. E. Stegeman, Greece, N. Y., assignor
to Bausch & Lomb Optical Company, Rochester, N. Y., a corporation of New York

Application July 22, 1952, Serial No. 20,715

Term of patent 14 years

(Cl. D57—1)

To all whom it may concern:

Be it known that I, Raymond F. E. Stegeman, a citizen of the United States and a resident of the town of Greece, county of Monroe, and State of New York, have invented a new, original, and ornamental Design for a Spectacle Case, of which the following is a specification, reference being had to the accompanying drawing, forming a part hereof.

Fig. 1 is a perspective view of a spectacle case, showing my new design.

Fig. 2 is an elevational view of one end thereof.

Fig. 3 is a side elevational view thereof.

I claim:

The ornamental design for a spectacle case, substantially as shown.

RAYMOND F. E. STEGEMAN.
